[57] CLAIM

The ornamental design for a wall-mounted bicycle rack, as shown and described.

DESCRIPTION

FIG. 1 is a top, front, and right side perspective view of a wall-mounted bicycle rack showing my new design; FIG. 2 is an enlarged front elevational view thereof; FIG. 3 is an enlarged top plan view thereof; FIG. 4 is an enlarged rear elevational view thereof; FIG. 5 is an enlarged bottom plan view thereof; and, FIG. 6 is an enlarged right side elevational view thereof, the left side being a mirror image of that shown.
